Primary Examiner — Catherine R Oliver-Garcia(57) **CLAIM**

The ornamental design for a fishing tackle, as shown and described.

DESCRIPTION

FIG. 1 is a front perspective view of a fishing tackle showing my new design;
 FIG. 2 is a rear perspective view thereof;
 FIG. 3 is a front elevational view thereof;
 FIG. 4 is a rear elevational view thereof;
 FIG. 5 is a left side elevational view thereof;
 FIG. 6 is a right side elevational view thereof;
 FIG. 7 is a top plan view thereof;
 FIG. 8 is a bottom plan view thereof;
 FIG. 9 is a perspective view of the fishing tackle shown in an open state;
 FIG. 10 is an enlarged view of an oval portion 10 of FIG. 1;
 FIG. 11 is an enlarged view of a circle portion 11 of FIG. 2;
 FIG. 12 is an enlarged view of an oval portion 12 of FIG. 2;
 and,
 FIG. 13 is an enlarged view of an oval portion 13 of FIG. 4. The broken lines in the drawings depict portions of the fishing tackle that form no part of the claimed design. The dash-dot-dash lines in the drawings are for the purpose of depicting boundary lines of the enlarged views and form no part of the claimed design.
